(57) **CLAIM**

The ornamental design for a Christmas tree topper bow, as shown and described.

DESCRIPTION

FIG 1 is a perspective view of a Christmas tree topper bow, showing my new design;

FIG. 2 is a front view thereof;

FIG. 3 is a rear view thereof;

FIG. 4 is a right side view thereof;

FIG. 5 is a left side view thereof;

FIG. 6 is a top plan view thereof; and,

FIG. 7 is a bottom plan view thereof.

The broken lines shown in the drawings represent portions of the Christmas tree in FIG. 1 that form no part of the claimed design. The surface shading illustrated in the drawings is provided merely to highlight the contour of the design; it is not intended to be illustrative of texture or gloss.
